(57) **CLAIM**

The ornamental design for a stimulation device as shown and described.

DESCRIPTION

FIG. 1 is a perspective view of a stimulation device.

FIG. 2 is a right side view of the stimulation device.

FIG. 3 is a left side view of the stimulation device.

FIG. 4 is a front view of the stimulation device.

FIG. 5 is a rear view of the stimulation device.

FIG. 6 is a top view of the stimulation device; and,

FIG. 7 is a bottom view of the stimulation device.

The broken lines shown in the drawings are for the purpose of illustrating portions of the stimulation device, which form no part of the claimed design.
